UNITED STATES PATENT OFFICE.

ARTHUR J. KAHN, OF NEW YORK, N. Y.

SPOOL-HOLDER.

1,321,050.

Specification of Letters Patent.

Patented Nov. 4, 1919.

Application filed April 3, 1919. Serial No. 287,312.

To all whom it may concern:

Be it known that I, ARTHUR J. KAHN, a citizen of the United States, and a resident of the city of New York, borough of Manhattan, in the county and State of New York, have invented a new and Improved Spool-Holder, of which the following is a full, clear, and exact description.

It is a well-known fact that holders for 10 spools have been constructed with a view of rotatably mounting a spool upon a table, or similar support, so that the thread may be conveniently handled without becoming entangled.

15 In previous devices of this nature, it has been found that the same have proven impracticable, for one or two reasons. The first reason is that they were more or less complicated; the second, that where simplicity was kept in mind they were usually provided with a screw, or other suitable clamping device for applying the holder to the supporting member, such as a table, the clamping device being usually located below 20 the level of the table, and in view of the flanges, legs, etc., which wound down under the deck of the table, it was often impracticable to firmly apply the holder to the table without marring certain parts of the 25 furniture to which it was applied.

30 I have now devised a spool holder which shall consist of only three parts, which parts are interconnected. Necessarily, I have provided the holder with means for securing it to the top of a table, or other piece of furniture, but I have constructed this fastening means in such a manner that no possibility of the same marring the furniture can occur, as it is at all times readily accessible.

35 A further object of the invention is to provide a holder in which the fastening device serves as the prong upon which the spool itself is mounted.

40 A final object of the invention is to provide a holder of this nature which shall be so simple in construction as to be capable of being produced, on a quantity bases, at such a cost that the same may be readily obtainable by any one.

Attention is invited to the accompanying drawings which illustrate one practical embodiment of this invention, and in which—

45 Figure 1 is a sectional side elevation of the deck of a table, or other piece of furni-

ture, to which the spool holder has been applied, certain parts of such spool holder being also illustrated sectionally;

Fig. 2 is an enlarged detail elevation, partly in section, of certain parts of the 60 device; and

Fig. 3 is a sectional view taken on the lines 3—3 of Fig. 2.

In these drawings the reference numeral 1 indicates the deck, or other suitable support, 65 for a holder, which includes a U-shaped bracket 2, preferably provided with a reinforcing flange 3 and a head 4 formed with an interiorly screw-threaded opening 5 in which is mounted a spindle 6.

The spindle 6 includes an ornamental head 7 below which is located a finger grip 8, which makes the spindle capable of being turned. A suitable distance below the hand grip 8 the spindle 6 is provided with screw 75 threads 9 engaging the screw-threaded opening 5. The lower end of the spindle 6 is mashed out so as to form a flange 10, and a washer 11 provided with inturning ends is rotatably mounted upon such flange by 80 means of overlapping flanges 12. Secured to the lower face of the washer 11, by means of pasting or any other suitable manner, is a felt disk 13. Similarly secured to the upper face of the opposite arm of the U- 85 shaped bracket 2, is a washer 14.

In operation it will now be seen that all that it is necessary to do to use this holder is for the spindle 6 to be rotated in an anti-clockwise direction, by means of the hand 90 grip 8, until sufficient space exists between the washers 13 and 14 to permit of the insertion therebetween of the support 1. When this latter operation has been completed the spindle 6 may be moved downwardly, by moving the same in a clockwise direction by means of the hand grip 8, until the washers 13 and 14 firmly clamp against the upper and lower faces respectively of the supporting member 1. The spool may 100 now be slipped upon the spindle 6. It will be seen that the clamp is so constructed that the furniture cannot be marred, and that a minimum number of parts are incorporated in this construction.

105 Further, I wish it understood that the head 4 may be entirely dispensed with, so that the arm of the bracket 2 may correspond to the arm upon which the washer 14 is mounted. The spindle 6 may be of any 110

length, and the distance between the jaws of the bracket 2 may vary, also, the reinforcing edge 3 may be eliminated entirely.

Further, it will be appreciated that I may 5 secure the washer 12 to the spindle 6 in any manner as long as the same may be freely rotated with respect thereto.

Having now described my invention, what I desire to claim is:

- 10 1. A spool holder, including a U-shaped bracket provided through the outer end of one of its arms with a screw-threaded opening, and a spindle having a portion of its body formed with screw threads adapted to engage with the screw threads and project through the opening formed in the U-shaped member, the inner face of the opposite arm of such U-shaped member and the lower end 15 of the spindle coöperating as a clamp whereby to hold the whole in applied position, the
- 20

upper end of such spindle being adapted to receive a spool.

2. A spool holder, including a U-shaped bracket provided through the outer end of one of its arms with a screw-threaded opening, a spindle having a portion of its body formed with screw threads adapted to engage with the screw threads and project through the opening formed in the U-shaped member, the lower end of such spindle being 25 formed with a flange, and a washer having its edges bent around such flange and rotatable with respect thereto, the inner face of the opposite arm of such U-shaped member and the outer face of such washer serving as 30 a clamp to retain the whole in applied position upon any desired object, the outer end of the spindle being adapted to receive a spool.

ARTHUR J. KAHN.
